(57) **CLAIM**

We claim the ornamental design for a headlamp light unit, as shown and described.

DESCRIPTION

FIG. 1 is a top perspective view of a headlamp light unit, shown in a position of use with a broken line environment; FIG. 2 is a top perspective view thereof, shown in an alternate position of use with a broken line environment; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict environment and portions of the headlamp light unit that form no part of the claimed design.
